CHAIR

John S. Burdick, North Muskegon, Mich., assignor
to The Shaw-Walker Company, Muskegon,
Mich., a corporation of Michigan

Application August 2, 1950, Serial No. 11,545

Term of patent 14 years

(Cl. D15—1)

To all whom it may concern:

Be it known that I, John S. Burdick, a citizen of the United States, residing at North Muskegon, in the county of Muskegon, State of Michigan, have invented a new, original, and ornamental Design for a Chair, of which the following is a specification, reference being made to the accompanying drawing, forming part thereof, wherein:

Figure 1 is a front view of a chair showing my new design;

Figure 2 is a side view of a chair showing my new design; and

Figure 3 is a three-quarter perspective view of a chair showing my new design.

Figure 4 is an enlarged detail section of the beaded skirt forming the horizontal frame for the chair seat.

The design is characterized by a relatively wide skirt having parallel horizontal beading thereon, and the contrasting appearance as shown.

I claim:

The ornamental design for a chair, as shown and described.

JOHN S. BURDICK.
